UNITED STATES PATENT OFFICE.

OSCAR A. ERICSON, OF CHICAGO, ILLINOIS, ASSIGNOR TO W. W. KIMBALL COMPANY, OF CHICAGO, ILLINOIS, A CORPORATION OF ILLINOIS.

PLAYER-PIANO UNIT.

Application filed December 11, 1922. Serial No. 606,049.

To all whom it may concern:

Be it known that I, OSCAR A. ERICSON, a citizen of the United States, residing at Chicago, in the county of Cook and State 5 of Illinois, have invented certain new and useful Improvements in Player-Piano Units, of which the following is a specification.

This invention relates to player pianos, and has for its main object to simplify and 10 render more compact certain elements of the player mechanism and to facilitate the testing and subsequent installation thereof in the piano case. The present invention deals with elements that are for the most 15 part commonly located in the lower portion of the piano case below the level of the keybed, such as the exhausters, vacuum reservoir or stabilizer, bass and treble action cut-offs, bass and treble expression controllers or governors, tempo regulator, motor air regulator, re-roll mechanism, and various 20 other adjunctive devices. Heretofore it has been the usual practice to construct and mount these various devices independently 25 within the piano case, attaching them to the walls of the latter or to internal supporting frame work, and uniting them for cooperative action through the agency of suitable hose connections. Such construction ob- 30viously requires these parts to be separately assembled and mounted within the piano case, and to be tested after they have been so assembled; and if the test is unsatisfactory, they must be removed, corrected 35 and then remounted and reassembled.

With a view to obviating these objections, as well as simplifying the structure and rendering it more compact and reliable, my present invention contemplates, as its chief 40 novel structural principle, an organization or assemblage of these various elements, or certain of them, in a single unitary rigid structure capable of being bodily applied to and removed from the piano case, and 45 also capable of being tested on the bench before installation in the instrument; the unit being further characterized by novel features of structure and arrangement whereby certain of the elements are placed 50 in direct communication with each other for the flow of the air, without requiring to be coupled up through the intervention of pipes and hose as heretofore.

The principle of my invention, its novel 55 features of structure and organization, and

the advantages attendant thereon will be readily understood by persons skilled in the art from the following detailed description, taken in connection with the accompanying drawings wherein I have illustrated a practical and approved embodiment of the principle of the invention, and in which—

Fig. 1 is a front elevation of my improved player piano unit, showing the pedals in 60 folded position;

Fig. 2 is a rear elevation of the unit;

Fig. 3 is a top plan view, with the pedals shown in unfolded or working position;

Fig. 4 is an end elevation, viewed from the right of Fig. 3, and showing the position of the unit in a piano case;

Fig. 5 is an enlarged vertical section on the line 5—5 of Fig. 1;

Fig. 6 is an enlarged vertical section on the line 6—6 of Fig. 1;

Fig. 7 is a face view of the automatic expression governor, with the front plate removed to show interior parts;

Fig. 8 is a face view of the action cut-off with the front plate removed to show 80 interior parts;

Fig. 9 is a face view of the combined tempo regulator, motor air regulator and re-roll device, with the front plate removed to disclose interior parts, and the regulator 85 pneumatic in section;

Fig. 10 is a vertical section on the offset line 10—10 of Fig. 9;

Fig. 11 is a vertical section on the offset line 11—11 of Fig. 9;

Fig. 12 is a horizontal section through the valve box in the plane of the line 12—12 of Fig. 13;

Fig. 13 is a vertical longitudinal section through the valve box on the line 13—13 of Fig. 12;

Fig. 14 is a horizontal section through the valve box in a plane of the line 14—14 of Fig. 13;

Fig. 15 is an enlarged vertical transverse 100 section through the valve box on the line 15—15 of Fig. 13; and

Fig. 16 is a central vertical transverse section through the valve box on the line 16—16 of Figs. 1 and 13.

The unit herein shown is designed for a divided player action; that is, one wherein the treble and bass portions are independently controlled.

Referring to the drawings, 5 designates as 110

an entirety a narrow hollow horizontally disposed box that extends the full width of the unit and constitutes a single unitary wind trunk; this hollow box also possessing 5 the additional functions of a vacuum stabilizer and wind conductor. Attached at their upper ends to the rear side of the end portions of the wind trunk 5 are a pair of depending blocks 6 and 7, hollowed out to 10 form wind passages as hereinafter described and constituting base members of the action cut-offs and the expression governors.

Attached at their upper ends to and extending below the rear side of the wind 15 trunk 5 are the usual exhausters 8, operated by the pedals 9, which latter are shown in Fig. 1 in folded position. The exhausters 8 communicate with the wind trunk 5 through valved ports 10 (Fig. 1) in its rear 20 wall. At one side of the exhausters 8 is located the main vacuum stabilizer or reservoir 11, this latter also being attached at its upper end to and extending below the rear side of the wind trunk 5 and communicating 25 with the latter through ports 12 (Fig. 1) in its rear wall.

At the ends of the wind trunk 5 are located valve mechanisms designated as an entirety by 13 and commonly known as action cut-offs, which serve to cut off the air current between the exhausters and the vacuum trunk of the player action when the record sheet is being re-rolled, so as to render the player action idle during the 30 re-rolling of the music sheet; and directly below the action cut-offs 13 are the expression governors or controllers designated as an entirety by 14, these latter being attached to the front faces of the blocks 6 and 7. Since 35 the action cut-offs and expression governors for the base and treble sections of the player action are identical, a description of one will suffice.

Mounted in the outer edge of each block 40 6 and 7 is a nipple 15 connected by a hose up to the vacuum trunk of the player action. The inner end of the nipple 15 communicates directly with an oval port 16 (Fig. 7) formed through the front face of the block 50 6 and the rear stationary wall of the automatic expression-governing pneumatic that is attached to the front face of the said block. This port 16 communicates with the chamber of the pneumatic, the movable side 55 of which latter is designated by 17, the same being hinged at its lower end. From the chamber of the pneumatic the air flows through a port 18 (Figs. 5 and 7) in the lower portion of its stationary rear wall 60 into an elongated duct or chamber 19 formed in the block 6 and extending nearly to the top of the latter, where it communicates with a hole 20 formed through the front face of the block and extending also through 65 a solid end portion 5a of the wind trunk

5 and through the bottom wall of an oblong chamber 21 that is formed in a block 22 attached to the front face of the wind trunk, said chamber being closed by a removable cover plate 23. From the chamber 21 the air flows through a port 24 (Figs. 6 and 8) in the bottom wall of the chamber into a shallow valve chamber 25 in the wind trunk that communicates freely at one side with the interior of the latter. Within 75 the chamber 25 is mounted a pouch pneumatic 26, the front face of which constitutes a cut-off or gate valve controlling the port 24; this pneumatic being normally deflated and held open by a light leaf spring 27 (Fig. 8) that is attached to the bottom wall of the chamber 21 and projects through the port 24, and bears on the front face of the gate valve.

The port 18 of the expression governor is automatically regulated as to capacity by a valve disk 28 mounted on the lower end of a lever 29 pivoted at 30 to the fixed side of the pneumatic and having a forwardly projecting upper end 31 that, when the movable side of the pneumatic is drawn inwardly by the vacuum against the tension of a pull spring 32, strikes the upper end 31 of the valve lever, and partially closes the port 18, thereby reducing the strength 95 of the suction; the valve 28, on the other hand, opening under the thrust of a torsion spring 33 acting on the valve lever 29, when the suction is lessened and the movable side of the pneumatic swings outwardly 100 under the pull of its spring 32. In the upper end of the rear fixed side of the expression governor is a port 34 that communicates directly with the passage 19 of the block 6 and is normally closed by a pouch pneumatic 35, which latter, when deflated, is opened by a light leaf spring 36 (Fig. 7) to provide a direct and unrestricted communication from the interior of 105 the governor pneumatic to the wind passage 19 when it is desired to obtain a forte effect.

Attached to the front wall of the wind trunk is a combined tempo regulator, motor air regulator or stabilizer, and re-roll mechanism, the details of which are shown in 110 Figs. 9, 10 and 11. This includes a box designated as an entirety by 37, the interior of which is divided by a longitudinal partition 38 and a vertical partition 39 into an upper chamber 40 and two lower chambers 41 and 42. In the rear wall of the chamber 42 is an oblong port 43 communicating with the interior of the wind trunk 5, said port 43 being automatically regulated as to 115 size by a pivoted throttle valve 44 connected to and actuated by the movable side of an underlying governor pneumatic 45, the interior of which pneumatic communicates freely with the chamber 42 through 120 a port 46. In the partition 38 is an oblong 125

port 47 controlled by the usual lever-operated sliding tempo valve 48 which, by a greater or less opening of the port 47, governs the speed of the motor, the speed 5 being maintained constant for any set position of valve 48 by the governor pneumatic 45 and throttle valve 44. The upper chamber 40 communicates freely through an elbow nipple 49 and a hose 50 with the music 10 roll motor.

In the partition 38 is another port 51 normally closed by a hinged flap valve 52, this latter being opened when the motor is reversed, to effect the rapid rewinding or 15 re-rolling of the music sheet, by a pouch pneumatic 53 located in the chamber 41; this latter chamber being in free communication with the wind trunk 5 through a port 54 (Fig. 9).

20 Attached to the face of the main vacuum reservoir or stabilizer 11 is a valve box designated as an entirety by 55 which contains pneumatically operated valves that effect the closing of the action cut-off or gate 25 valves 26, the opening of the forte expression valves 35, and the opening of the re-roll valve 52, through the manual manipulation of the usual buttons or levers (not shown) on the keybed of the instrument. The details of this valve box are shown in Figs. 30 12 to 16 inclusive. In the center of this box is a normally closed mushroom valve 56, the operating diaphragm 56' of which is expanded by atmospheric air admitted through 35 a nipple 57 and a hose connected to the latter when the appropriate button in the keybed is depressed. The raising of the valve 56 allows atmospheric air to flow through tubes 58 and ducts 59 (Figs. 6 and 8) into 40 the pouches of the action cut-off or gate valves 26, and also at the same time permits atmospheric air to flow through duct 60 to the operating pneumatic 53 of the re-roll valve 52, opening the latter. On either side 45 of the central valve 56 is a valve 61 controlling a port 62 open to the atmosphere through the top wall of the box 55, and normally open so as to permit atmospheric pressure to flow through the port 50 62, duct 63' (Fig. 12), hose 63 (Fig. 1) and duct 64 (Figs. 2 and 5) to each of the forte expression valves 35 expanding the pouch of the latter and maintaining the expression valve in closed position. When, however, the appropriate button in the keybed is depressed, air is admitted through a hose 65 and nipple 66 beneath the operating diaphragm 61' of the valve 61, raising the latter, closing port 62, 55 and placing the duct 63' in communication with the vacuum chamber 55' of the box 55, which chamber is in open communication with the vacuum reservoir or stabilizer 11 through a port 67 (Figs. 14 and 16) and 60 65 thus subject to the vacuum of the reservoir.

latter. This creates equal pressure conditions on opposite sides of the forte expression valve 35 and the latter is instantly opened by its spring 36.

For the purpose of rigidly mounting the 70 described parts assembled as a unit in the lower portion of the piano case, I attach to the front stationary faces of the two ex- hausters 8 a pair of depending blocks 68, to the front faces of which are attached iron strips 69 each having on its lower end a for- wardly extending substantially horizontal forked foot 70 adapted to receive fastening screws screwed into a base block 71 of the piano case (Fig. 4); and to the front face 80 of the wind trunk 5, centrally thereof, I attach an iron strip 72, the upper end portion of which projects above the wind trunk and is removably engaged with a locking notch 73 in a leaf spring 74 attached to the 85 under side of the keybed. Thus, by the tightening and loosening of two screws and the upward bending of spring 74, the unit may be bodily mounted in and removed 90 from the piano case by simply withdrawing the usual removable lower front panel of the latter.

The advantages of the invention will be readily understood from the foregoing description. By means of the unitary structure, the various co-operating elements are manifestly assembled in a very compact relation. By connecting the elements for the flow of the air current for the most part directly by registering ports, instead of through the intermediary of nipples and hose, a considerable economy of material is effected, and the air passages are rendered more direct. The main advantage, however, resides in the fact that the construction admits of the complete assembling and testing of the unit before it is installed in the piano case, thereby obviating the necessity of first separately mounting and then connecting up the several elements within the piano case, and subsequently removing them in case the test discloses faulty construction at any point or points.

I claim:—

In a player piano apparatus, the combination of a horizontally disposed box forming a wind trunk, exhausters directly attached at their upper ends to a wall of said box and communicating with the latter through registering ports formed in their contacting walls, a vacuum reservoir directly attached at its upper ends to a wall of said box alongside said exhausters and communicating with said box through registering ports formed in their contacting walls, treble and bass action cut-offs directly mounted on and communicating interiorly with the end portions of said box, respectively, treble and bass expression governors rigidly connected to said box and communicating interiorly 115
120
125
130

with the latter through said action cut-offs, a tempo regulator and re-roll valve both directly mounted on said wind trunk and communicating with the latter through 5 registering ports formed in their contacting walls, a pneumatically operated control-valve mechanism mounted on said vacuum reservoir and communicating directly with

the latter through registering ports, air conductors connecting said control-valve mechanism with said action cut-offs, expression governors and re-roll valve, and means for mounting said parts as a unit within the lower portion of the piano case. 10

OSCAR A. ERICSON.
